LAMP

Henry L. Zelchenko, Shrub Oak, N. Y.

Application November 19, 1948, Serial No. 149,719

Term of patent 3½ years

Cl. D48—20)

To all whom it may concern:

Be it known that I, Henry L. Zelchenko, a citizen of the United States of America, residing at Shrub Oak, Westchester County, New York, have invented a new, original, and ornamental Design for a Lamp, of which the following is a specification, reference being had to the accompanying drawing, forming part thereof wherein:

The figure is a perspective view of a lamp showing my new design, both sides thereof being the same.

I claim—

The ornamental design for a lamp, as shown and described.

HENRY L. ZELCHENKO.
